UNITED STATES PATENT OFFICE.

NELSON TROYER, OF ASTORIA, OREGON.

DIE FOR FORMING CAN-HEADS.

SPECIFICATION forming part of Letters Patent No. 531,451, dated December 25, 1894.

Application filed May 24, 1894. Serial No. 512,341. (No model.)

To all whom it may concern:

Be it known that I, NELSON TROYER, a citizen of the United States, residing in Astoria, in the county of Clatsop and State of Oregon, 5 have invented a new and useful Improvement in Dies for Forming Can-Heads, of which the following is a specification.

This invention relates to an improved cutting, stamping and creasing die for making 10 from sheet metal, creased, key-opener can heads.

The nature of the invention will be understood from the following description and 15 claims, taken in connection with the accompanying drawings, in which—

Figure 1 is a central vertical section of the device. Fig. 2 is a fragmentary section of the same upon a larger scale. Fig. 3 is a bottom view of the face of the upper die, 20 upon a smaller scale than Fig. 1. Fig. 4 is a top view of the can-head as made by the die, being upon the same scale as Fig. 3 and Fig. 5 is a sectional view of said can head shown in Fig. 4.

25 In said drawings A is the upper die stock and B the lower die stock.

a is the cutting ring of the die stock and b the cutting ring of the lower die stock. The ring a is made removable from the die stock, 30 being screwed thereon by means of the screw thread a' so that it is capable of being fed downward as the cutting edge wears away.

a² is a jam-nut for locking the cutting ring in its proper position. Inside of the cutting 35 ring I place in the die stock A two rings C C' made of hardened steel, separated from each other by the soft steel ring D. The outer one, C, of the two hardened rings is supported partly by and against the cutting 40 ring a which is furnished with a ledge a³ for this purpose; and the inner one, C', is supported partly by and against the soft steel ring D, which is furnished with a ledge d for this purpose.

45 E is the central movable portion of the die upon which is placed the key-form projection for making in the head of the can the countersunk recess to receive the key. This movable part E serves as the knock out for the 50 die. The face of the upper die it will be noticed is composed of the cutting ring a, the ring D, the exposed lower surface of the

die stock A, the piece E and the lower inner corners of the two hardened steel rings C, C', which corners are marked respectively c 55 and c'.

A description of the lower die stock and its parts will be unnecessary as the same is already familiar to those skilled in this art, who will understand it and its operation from 60 the drawings. It will be necessary only to note in relation to this lower or counteracting die that B' is a solid ring having the curved upper surface b' to counter the form of the face of the ring D in the upper die. 65

The sheet from which the can head is to be formed is fed between the dies in any suitable manner and the upper die being brought down upon it, the blank is cut out by the descent of the upper die, and by a further 70 movement is forced into the shape shown at Figs. 4 and 5. At the same time the inner lower corners c, c' of the hardened steel rings C, C', set into the metal of the can head, forming the creases i, i' by a partial severing 75 of the blank at these lines. The principal wear of the die, and the greatest pressure encountered will be found at these corners c and c', which actually penetrate the metal of the sheet to a greater or less extent, and 80 these corners must be kept sharp.

It will be noticed that the two hardened steel rings C and C' are easily removed from the die by screwing off the ring a, and being removed can readily be ground and sharpened as occasion requires. It will also be noticed that these hardened steel rings are firmly supported at top and sides by the die stock, the ring a and the intermediate ring D, so that no matter how severe the strain or 90 pressure put upon them, there is no liability for them to break or yield in any direction under strain. 85

I prefer to surround the ring a with a reinforcement of tough soft steel which is shown 95 in the drawings and forms a part of said ring a, but is not separately lettered, but can be seen as surrounding the ring a. This reinforcing ring also affords the necessary body of metal in which the usual spring holders— 100 one of which is shown, but not lettered—may be mounted.

I claim—

1. In a die for forming sheet metal can

heads, the combination of the die stock, the cutting ring *a* removably secured to the die stock, and the removable hardened steel rings *C C'* having the sharpened corners *c c'* exposed to come in contact with the sheet metal blank, substantially as specified.

2. In a die for forming sheet metal can heads, the combination of the die stock, the cutting ring *a* removably secured to the die

stock, the removable hardened steel rings *C C'* having the sharpened corners *c c'* exposed to come in contact with the sheet metal blank, and the intermediate ring *D*, substantially as specified.

NELSON TROYER.
